(57) **CLAIM**

The ornamental design for a surgical safety knife as shown and described.

DESCRIPTION

FIG. 1 is a perspective view of a surgical safety knife in a shielded state;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof; and,

FIG. 7 is a front elevational view thereof;

FIG. 8 is a perspective view of a surgical safety knife in a use state;

FIG. 9 is a top plan view thereof;

FIG. 10 is a bottom plan view thereof;

FIG. 11 is a left side elevational view thereof;

FIG. 12 is a right side elevational view thereof;

FIG. 13 is a rear elevational view thereof; and,

FIG. 14 is a front elevational view thereof.

The broken lines depict a blade and interior portions of the shield of the surgical safety knife. The broken lines and unshaded regions bound on all sides by broken lines illustrate portions of the surgical safety knife that form no part of the claimed design.

1 Claim, 12 Drawing Sheets
